UNITED STATES PATENT OFFICE

2,428,902

PADLOCK

Leonard Weare Young, Northwood, England

Application March 16, 1945, Serial No. 583,046
In Great Britain November 12, 1943Section 1, Public Law 690, August 8, 1946.
Patent expires November 12, 1963

4 Claims. (Cl. 70—40)

1

The object of the present invention is to provide a padlock of simple construction which will be much more secure against forcible release than those at present in use.

The improved padlock comprises a hollow housing or barrel having a slot in its margin for the entry of the hasp, a rotatable disc occupying the interior of the housing and formed with a slot the centre line of which is preferably displaced from the axis of rotation of the disc, and a lock for locking the disc in a position in which the slot in its margin is transverse to the slot in the edge of the housing.

The interior of the housing may conveniently be cylindrical to fit the cylindrical edges of the disc, which thus rotates within the housing without the necessity of a central pivot pin.

The lock may be of any convenient type; for example the lever type or of the pin tumbler type. In the latter case the spring-pressed tumblers may be housed in bores in the edge of the disc and co-operate with pins sliding in bores in the housing and operated by a key which can be inserted in a key hole in the housing. It is preferred, however, to provide a separate tumbler-lock cylinder mounted in the body portion of the housing. This cylinder is provided with a locking member co-operating with a shoulder on the edge of the disc so that in one position of the cylinder the locking member engages the shoulder to prevent rotation of the disc while in another position to which the cylinder can be turned by the key the locking member is out of engagement with the shoulder, with the result that the disc can be turned to release the hasp.

The slots in the housing and in the disc may be arranged so that the hasp will co-operate with the edges of the slots to rotate the disc in either direction. Alternatively the slots may be so arranged that although the insertion of the hasp will turn the disc into the locked position, an attempt to withdraw the hasp will be ineffective to turn the disc into the unlocked position, the two slots being substantially perpendicular to one another. In this case an arcuate slot is provided in the cover plate for the insertion of a screw-threaded pin into a screw-threaded hole in the disc after the padlock has been assembled. This pin projects beyond the outer surface of the cover plate and provides

2

a means whereby the disc can be rotated readily.

According to a further feature of the invention means are provided whereby the lock mechanism can be assembled with the housing after the cover plate has been secured in position. Thus, the cover plate may be secured to the body portion of the housing by a method involving heat, for example brazing, welding or the like, without drawing the temper of the springs forming part of the lock mechanism.

Referring to the accompanying drawings:

Figure 1 is a side elevation in section of one form of padlock in the open position;

Figure 2 is a similar view showing the padlock in the closed position;

Figure 3 is a section along the line III—III in Figure 1;

Figure 4 is a section along the line IV—IV in Figure 2;

Figure 5 is a view similar to Figure 1 of a modified construction;

Figure 6 is a similar view of another modification;

Figure 7 is a section along the line VII—VII in Figure 6;

Figure 8 is a view similar to Figure 1 of a further modified construction; and

Figure 9 is a side elevation of Figure 8 with the cover plate in position.

Referring to Figures 1 to 4, a housing 10 is formed with a cylindrical recess 12 in which rotates a cylindrical disc 14 constituting a shackle. The housing is formed with a slot 16 which is offset slightly to one side as shown:

The disc 14 is formed with a similar slot 18 which is also offset—that is to say its centre line is displaced from a diameter of the disc.

When the entrances to the two slots are in register as shown in Figure 1, one side of the slot 18 is presented at an angle to the slot 16. When the hasp 20 to which the padlock is to be secured is inserted it will co-operate with the inclined surface to cam the disc 14 round to the closed position shown in Figure 2. The opposite edge 45 of the slot 18 is then presented at an angle such that when the hasp is pulled outwards along the slot 16 the disc is returned to the open position, releasing the hasp.

The disc 14 is formed with a notch 22 which extends across the whole width of the disc and

this notch communicates with a recess 24 the depth of which is one half of the width of the disc. The notch 22 receives the inner end 26 of a cylinder 28 similar to the cylinder of an ordinary pin tumbler lock, carrying pins sliding in transverse bores and co-operating with spring-pressed tumblers 30 sliding in bores in the housing 10. Normally these tumblers lock the cylinder in the position shown in Figure 2 but the insertion of a correct key frees the cylinder and enables it to be rotated. The end 26 of the cylinder is cut away as clearly shown in Figures 3 and 4 to semi-cylindrical shape. In the position shown in Figures 2 and 4 this part 26 is in engagement with the right hand side of the notch 22 thereby preventing the disc 14 from rotating in the clockwise direction, while rotation in the anti-clockwise direction is of course prevented by engagement of the part 26 with the left hand side of the notch. When the cylinder 28 is rotated by the key into the position shown in Figures 1 and 3, the part 26 is in register with the recess 24 and no longer in engagement with the right hand side of the notch 22. Thus the disc 14 can turn as previously described into the position shown in Figure 1 to release the hasp 20.

The bore in the housing 10 for the cylinder 28 is counterbored as at 32 to receive the end of an outwardly spring-pressed pin 34 mounted to slide radially in a bore in the cylinder. When the cylinder is first inserted in the housing this pin 34 is pressed inwards but when the cylinder is completely inserted the pins spring outwards into the counterbore 32, thereafter preventing the withdrawal of the cylinder. Steps (not shown) may be provided in the counterbore for engagement with the pin 34 to limit the rotation of the cylinder to 180°.

It is evident that the cylinder 28 and the tumblers 30 and their springs can be inserted after the cover plate 36 (Figures 3 and 4) has been secured to the housing 10. It is therefore possible to secure the cover plate to the housing by brazing, spot welding or a like operation involving heating, which would be impossible if the tumblers and their springs had to be assembled with the padlock before the cover plate is secured in place.

Preferably the disc 14 is formed with a projection 38 engaging in an arcuate recess 40 in the cylindrical side of the recess 12. This ensures that the disc 14 is in a position, after the cover plate has been secured, in which either the notch 22 or the recess 24 will receive the end 26 of the cylinder.

It will be appreciated that when the cylinder is in the position shown in Figure 1 the key cannot be withdrawn and the disc 14 cannot be locked in the open position. In the modified construction shown in Figure 5 a second notch 23, similar to the notch 22, is provided which, when the disc is in the open position, is in register with the part 26 of the cylinder, enabling the cylinder to be turned back to the locked position in which the key can be withdrawn, the disc 14 then being locked in the open position. If the padlock has the dimensions and proportions shown, the part 26 of the cylinder 28 must be of smaller diameter than the rest of the cylinder so that the two notches 22, 23 do not break into one another.

Referring now to Figures 6 and 7, the housing 10 and the disc 14 are generally similar to those shown in Figures 1 and 2. The cylinder 28, however, is arranged at right angles to the position that it occupies in Figures 1 and 2. Its inner

end 27 is squared to fit a square hole in a locking member 42 co-operating with a notch 44 in the periphery of the disc 14. As clearly shown in Figure 7, when the cylinder 28 is locked against rotation the locking member 42 is in engagement with the side of the notch 44 thereby locking the disc 14 in the closed position. When a correct key is inserted the cylinder can be rotated to move the locking member sideways out of engagement with the notch 44 thereby enabling the disc 14 to rotate into the open position to release the hasp.

Referring to Figures 8 and 9, the locking mechanism is of the combination type, consisting of a number of discs 46 formed with flats 48 in various angular positions relative to central slots 50 in the disc. These discs are threaded on a spindle 52 journalled in the disc 14 and having a projection 54 co-operating with the ends of the slots 50. This is a well known form of locking mechanism and need not be described in detail. The spindle 52 carries a knob 56 and a graduated dial 58 co-operating with an index 60 and this knob is turned to successive positions right and left according to the dialling required to align all the flats 48 in a position indicated by the dotted line in Figure 8 such that the disc 14 can rotate in the housing 10.

The disc 14 in Figures 8 and 9 differs from that shown in earlier figures in that when it is in the closed position the slot 16 is at right angles to the slot 18. The disc 14 however can be rotated into the open position merely by pulling the hasp outwardly along the slot 16 as in the constructions described above. It can also be rotated by means of the knob 56, a slot 62 being provided in the cover-plate of the housing to receive the spindle 52. This slot is covered up at all times by the dial 58. When some other form of lock is used, such as those shown in Figures 1, 2 and 6, a pin 64 (Figure 6) may be screwed into a hole in the disc 14, this pin projecting through a slot 66 in the cover-plate and providing a means whereby the disc 14 may be rotated. In some cases this pin may project from the edge of the disc through a slot in the edge of the housing.

It is evident that the cover plate may be secured to the housing by means of rivets or any other well known method, although in most cases brazing or welding will be preferred on account of their greater security.

What I claim is:

1. A padlock comprising a housing provided with a cylindrical bore and an offset marginal slot for the entry of a hasp, a cylindrical disc fitted in said bore, said disc having an offset hasp slot, said disc being rotatable from a first position where the mouths of said slots are in registry and the bottoms of the slots are out of registry to a second position where the bottoms of the slots are in registry and the mouths are not, and means for locking said disc in said second position.

2. A padlock according to claim 1 wherein the means for locking said disc in said second position comprises a locking member mounted in said housing, said rotatable disc being provided with a notch that provides a shoulder, said locking member being mounted for movement into and out of engagement with said shoulder, and key-operated means normally holding the locking member in locking position but capable of being disengaged by the operation of a key.

3. A padlock according to claim 1 wherein the means for locking said disc in said second position comprises a locking member, a rotatable disc being formed with a notch providing a shoulder, said

locking member being mounted in said housing to move into and out of engagement with said shoulder and being a part of the cylinder of a pin and tumble lock mounted for rotation in a bore in said housing.

4. A padlock according to claim 1 wherein the rotatable disc is formed with a notch providing a shoulder for coaction with the cylinder of a pin and tumbler lock mounted for rotation in a bore in said housing, said cylinder and shoulder constituting the means for locking said disc in said second position, said cylinder being semi-cylindrical at the end that coacts with said shoulder and the part of the rotatable disc that provides the shoulder being formed with a recess which is in registry with the semi-cylindrical end of the

cylinder so as to permit rotation of the disc when the cylinder is out of locking position.
